UNITED STATES PATENT OFFICE

EDWARD WALTON KEESEY, OF REDDITCH, ENGLAND, ASSIGNOR OF ONE-HALF TO THE
BRITISH NEEDLE COMPANY LIMITED, OF REDDITCH, ENGLAND

CONTAINER FOR GRAMOPHONE NEEDLES

Application filed July 30, 1930, Serial No. 471,775, and in Great Britain March 11, 1930.

This invention relates to containers for talking machine needles, and has for its object to provide improved means for disposing of used or spent needles.

5 The invention comprises a container of pyramidal, conical or like tapering form which is provided internally with compartments for both new and spent needles, the new needles being withdrawn singly through 10 an aperture in the apex of the container, and the spent ones reinserted through holes or slits in the base or sides of the container.

In the accompanying sheet of explanatory drawing:—

15 Figure 1 is a vertical section, Figure 2 a part sectional side elevation, and Figure 3 a plan of a preferred form of needle box constructed in accordance with this invention.

20 Figures 4 and 5 are respectively sectional views of a portion of a box shaped as shown in Figures 2-4 illustrating modified arrangements of the partition forming one side of the spent needle compartment.

25 The construction shown in Figures 2-4 comprises a pyramidal, conical or like tapered container *a* having an aperture *g* in its apex through which the needles can be shaken out singly. The interior of the container is divided internally by a partition *c* so as to 30 form in the base a compartment *e* for spent needles. This compartment is made accessible by the provision of one or more holes *f* or slits through which the needles can be inserted. The partition *c* is preferably arranged parallel with the base, but if desired it may be arranged vertically or obliquely. Figure 5 illustrates an obliquely disposed partition and Figure 6 shows the partition 35 arranged vertically. The vertical partitions indicated by *i* form no part of my invention. They serve to prevent jamming of the needles in the compartment *d* when the container is inverted and is shaken for expelling a needle 40 through the aperture *g*.

45 By this invention the inconvenience commonly associated with the disposing of spent or used gramophone needles is avoided in a very simple and satisfactory manner, the one 50 container being adapted to accommodate the

needles both before and after use. After all the needles have been used the container can be thrown away without risk of the contained needles becoming scattered.

Having thus described my invention what I claim as new and desire to secure by Letters Patent is:—

1. A container for talking machine needles, of tapering form, a delivery aperture in the apex of the container, a non-detachable partition dividing the interior into compartments for unused and used needles, and an aperture communicating with the used needle compartment, substantially as described.

2. A container for talking machine needles, of tapering form, a delivery aperture in the apex of the container, a horizontal non-detachable partition dividing the interior of the container into compartments for unused and used needles, and a side aperture communicating with the used needle compartment, substantially as described.

In testimony whereof I have signed my name to this specification.

EDWARD WALTON KEESEY.
